DESIGN FOR AN AUTOMOBILE EXHAUST SHROUD

Louis A. Koch, Jr., Louisville, Ky.

Application February 10, 1936, Serial No. 61,058

Term of patent 7 years

To all whom it may concern:

Be it known that I, Louis A. Koch, Jr., a citizen of the United States, residing at Louisville, in the county of Jefferson and State of Kentucky, have invented a new, original, and ornamental Design for Automobile Exhaust Shrouds, of which the following is a specification, reference being had to the accompanying drawing, forming part thereof.

Figure 1 is a plan view of an automobile exhaust shroud.

Figure 2 is a side elevational view showing my new design.

Figure 3 is a bottom view, while
Figure 4 is an end elevational view.

The dominant feature of this design resides in the part-circular or kidney shaped prismatic reflecting element conforming substantially to the inclined rear face of the shroud and uniformly framed by the periphery thereof.

I claim:

The ornamental design for an automobile exhaust shroud, as shown and described.

LOUIS A. KOCH.
